UNITED STATES PATENT OFFICE.

JACOB NIEMES AND HARRY B. ENGBERSEN, OF CHICAGO, ILLINOIS; BERTHA M. ENGBERSEN ADMINISTRATRIX OF SAID HARRY B. ENGBERSEN, DECEASED.

TANDEM ARRANGEMENT FOR PRINTING MACHINES AND THE LIKE.

Application filed August 18, 1922. Serial No. 582,325.

To all whom it may concern:

Be it known that we, JACOB NIEMES and HARRY B. ENGBERSEN, citizens of the United States, residing at Chicago, in the 5 county of Cook and State of Illinois, have invented a certain new and useful Improvement in Tandem Arrangements for Printing Machines and the like, of which the following is a full, clear, concise, and exact description, reference being had to the accompanying drawings, forming a part of this specification.

Our invention has for its main feature a tandem arrangement for printing machines 15 and the like which is simple, convenient, and well adapted for its purpose, and which does not require an excessive amount of floor space.

The invention contemplates in its preferred 20 form the use in the tandem arrangement of the piling table and sheet delivery supplied with certain printing presses as hereinafter set forth, and another feature resides in the provision of a tandem arrangement which 25 permits the use of this equipment without making radical changes in the construction or positions thereof as originally supplied, and which does not require an excessive amount of additional equipment or an excessive amount of labor in its installation.

The invention also contemplates in its preferred embodiment the use, as the second element of the tandem, of a sheet treating machine adapted for sheet feed and discharge from one end and having its sheet 35 discharge point below its point of sheet feed, and where such a machine is used as the second element of the tandem in the manner hereinafter set forth the required 40 changes on this machine are very simple.

Another feature of the invention has to do 45 with a sheet receiving means, preferably a piling table, and means for conveying sheets from either of two sheet treating machines and delivering them to the sheet receiving means whereby but one sheet receiving means is required for the two sheet treating machines, and where this arrangement is used with the tandem arrangement above set forth either machine may be operated by itself, the necessary means being supplied for operating the necessary parts for conveying and delivering from either machine.

The invention contemplates the use of a 55 printing press as the first sheet treating ma-

chine of the tandem and a bronzing machine as the second sheet treating machine of the tandem, and the arrangement is particularly advantageous in such an arrangement.

With these features in view our invention consists in certain features of novelty in the construction, combination, and arrangement of parts by which the said features and certain other features hereinafter appearing are effected, all as fully described with reference to the accompanying drawings and more particularly pointed out in the claims.

In the said drawings—

Figure 1 is a side elevation of a printing 70 press and bronzing machine coupled in tandem in accordance with our invention.

Figure 2 is an enlarged view of a portion of the tandem structure in similar elevation.

Figure 3 is an enlarged view of another portion of the tandem structure in similar elevation.

Figure 4 is an enlarged partial top plan view of the tandem structure.

Figure 5 is an enlarged side elevation of the bronzing machine taken on the side thereof opposite that shown in Fig. 1.

Like characters of reference indicate like parts in the various views.

In the said drawings 1 generally indicates a cylinder printing press of usual construction, 2, a bronzing machine of usual construction spaced from the front end of the printing press and disposed with its rear end facing the front end of the press, and 3, a piling table of usual construction disposed between the printing press and bronzing machine.

Sheets are received by an impression cylinder 4 of the press from a feed board 5 at the rear end thereof. The sheets are printed while carried by the impression cylinder, and after they are printed are carried forwardly from the impression cylinder by cylinder conveyor belts 6 which discharge the sheets upon conveyor belts 7 by which they are carried forwardly beyond the front end of the press. The inner ends of the belts 6 are supported in the usual manner and are driven from the impression cylinder by the usual gearing, and the outer ends of the belts 6 and the inner ends of the belts 7 are supported by a common transverse roller 8 rotatably mounted in delivery 110

frames 9 of the press whereby the belts 7 are also driven by the press, all as is usual. The outer or forward ends of the belts 7 are supported by belt pulleys 11 which are 5 carried by a transverse shaft 12 which is rotatably mounted at the outer end of a conveyor frame which is vertically adjustable by reason of parallel side bars 13 thereof being pivoted at their inner ends to the being 10 livery frames 9 as designated at 14. A pair of bell crank levers 15 are mounted at their angles on opposite sides of the top of the frame of the piling table 3 at the end thereof adjacent the press by means of studs 16. 15 Respective arms of these levers extend upwardly and the outer ends thereof are secured to the ends of a pair of parallel conveyor frame side bars 17 which are disposed some distance above the piling table 3 and 20 extend therefrom toward the bronzing machine and are secured to respective brackets 18 secured on the outer end of a feed board 19 of the bronzing machine 2. The levers 15 are thus angularly positioned on the 25 studs 16, and the other arms of these levers extend upwardly and toward the press and the outer ends thereof are secured to the lower ends of respective brackets 21 whose upper ends are secured to respective side 30 bars 13 adjacent their outer ends whereby the conveyor frame, in which the shaft 12, carrying the pulleys 11, is mounted, is supported in an upper position of its vertical adjustment with the outer ends of the tapes 7 disposed some distance above the piling table 3.

Belt pulleys 22 are carried by the bars 17, adjacent the end thereof supported by the levers 15, by means of spring tension 40 mountings 23 mounted on a transverse rod 24 extending between the bars 17 and secured thereto in a usual manner. A transverse roller 25 is rotatably mounted on the brackets 18, and conveyor belts 26 are supported on the pulleys 22 and roller 25 and extend some distance above the piling table. Belt pulleys 27 are carried by side bars 28 mounted on the feed board 19 of the bronzing machine 2 by means of spring tension 50 mountings 29 mounted on a transverse rod 31 extending between the bars 28 and secured thereto in a usual manner. Conveyor belts 32 are supported by the roller 25 and pulleys 27 and form a continuation of the sheet conveyor formed by the belts 26 supported by the pulleys 22 and roller 25.

The gap between the pulleys 11 and 22 is bridged by rods 33 mounted on brackets 34 detachably and adjustably mounted on a 60 transverse rod 35 extending between and secured to the side bars 13 in a usual manner. The sheets are discharged from the belts 7 over the rods 33 and on to the belts 26, which carry them to the bronzing machine and discharge them upon the belts 32, which carry

them inwardly over the feed board 19 of the bronzing machine. The sheets are guided into feeding position on the bronzing machine from the inner ends of the belts 32 by means of rods 36 mounted between the 70 bars 28 in a usual manner, and are fed to a sheet carrying cylinder 37 of the bronzing machine by the usual means not shown.

The bronzing machine 2 is adapted for sheet feed and discharge from the rear end 75 thereof, which faces the front end of the press 1, and has its discharge point disposed below its point of feed, and the sheets are discharged therefrom by belts 38 which are supported on a large transverse rotating belt reel 39, geared to the sheet carrying cylinder 37, and a transverse rotating belt roller 41 of the bronzing machine, the sheets being passed from the cylinder 37 over the reel 39 and onto the belts 38 by the usual means. 80 An elevated transverse belt roller 42 is rotatably mounted on the frame of the bronzing machine and extends within the enclosure of the belts 38. Support bars 43 are secured on opposite sides of the frame of the bronzing machine and extend outwardly in a rearward direction therefrom, and an elevated transverse belt roller 44 extends between and is rotatably mounted at the outer 85 ends of these bars. Conveyor belts 45 are supported on the rollers 42 and 44 and receive sheets from the belts 38 and carry them in a direction outwardly from the rear end 90 of the bronzing machine. Downwardly projecting supports 46 are secured on respective 95 bars 17 adjacent the end of the piling table 3 facing the bronzer, and extending between these supports and rotatably mounted at the lower ends thereof is an elevated shaft 47 which carries belt pulleys 48. Conveyor 100 belts 49 are supported on the roller 44 and pulleys 48 and receive the sheets from the belts 45 and carry them toward the piling table.

As before mentioned the reel 39 is geared 110 to the sheet carrying cylinder 37 of the bronzing machine, and the roller 42 is geared to the reel 39 whereby the belts 45 are driven from the bronzing machine, and the belts 49 are driven from the bronzing machine by reason of the belts 45 turning the roller 44. The roller 42 has a chain sprocket 51 secured thereto, and a sprocket chain 52 is engaged therewith and with one portion of a double sprocket 53 rotatably mounted on the frame of the bronzing machine whereby the double sprocket 53 is driven. See Fig. 5. The roller 25 has a chain sprocket 54 secured thereto, and a sprocket chain 55 is engaged therewith and with an idler sprocket 56 rotatably mounted on the frame of the bronzing machine. One stretch of the chain 55 is engaged with the other portion of the double sprocket 53 and the belt roller 25 is thus driven from the bronzing machine 125 130

whereby the belts 26 and 32 are driven therefrom.

Secured on the top of the frame of the piling table 3 are a pair of transversely spaced forwardly and rearwardly extending horizontal tracks 57, and mounted thereon for forward and rearward reciprocating movement below the belts 26 is a sheet delivery carriage of usual construction comprising a pair of trucks 58 secured together by a transverse rod 59, and sheet sticks 61 are secured to the rod 59 and extend horizontally therefrom in the direction of the bronzing machine and are disposed to pass over the shaft 47 between the pulleys 48 just below the upper stretch of the belts 49, the shaft 47 and roller 44 being positioned to dispose the upper stretch of the belts 49 in a horizontal plane. A transverse shaft 62 extends between the trucks 58 and is mounted thereon above the sheet sticks for oscillating movement, and has stop fingers 63 mounted thereon adapted to maintain a sheet from movement off the sticks from the ends thereof adjacent the rod 59 when the shaft 62 is in one position of its movement, as shown in Figs. 2 and 3, and to permit such movement of the sheet in an opposite position of the shaft. The shaft 62 is actuated at the respective ends of the stroke of the carriage by an arm 64 secured on the shaft and engaged by stops 65 mounted respectively on one of the bars 17 and one of the supports 46. Each sheet is received from the belts 49 on the sticks 61 of the delivery carriage with the fingers 63 in their sheet stopping positions and is so carried out over a platform 66 of the piling table. At the end of this stroke of the carriage the fingers 63 are raised by the arm 64 engaging the adjacent stop 65, and at the same time pusher fingers 67 are raised into the path of the sheet at the rear end thereof by reason of the actuation of a lever 68, by engagement of the rod 59 therewith, which rocks a transverse shaft 69, upon which the pusher fingers are mounted, through the medium of a connecting rod 71 connected with the lever 68 and a lever 72 secured to the shaft 69. Thereafter upon movement of the carriage in the opposite direction the sheet sticks move from under the sheet which is held stationary by the pusher fingers 67, and the sheet drops upon the platform 66 or upon a stack 73 of previously delivered sheets thereon. The pusher fingers 67 are moved out of the sheet path by the rod 59 engaging the same and the fingers 63 are moved to sheet stopping position by the engagement of the arm 64 with the other stop 65 with the final movement of the carriage in the opposite direction preparatory to carrying out another sheet for delivery. The carriage is reciprocated from a crank 74 secured on a cam shaft 75 of the press, which is geared to

and driven with the cylinder 4 thereof, by means of a connecting rod 76 pivotally connected with the crank and an arm 77 secured on a transverse rock shaft 78 extending between and rotatably mounted on the delivery frames 9 of the press, lever arms 79 secured on the shaft 78 adjacent respective ends thereof, and connecting rods 81 pivotally secured to respective arms 79 and trucks 58, all as is usual.

A top tape mechanism, generally indicated at 82, is provided for the conveyor belts, 6, 7, and the portion of the conveyor belts 26 adjacent the belts 7, and is driven from the press 1, all as is usual, the outer portion of this top tape mechanism over the belts comprising belts 83 supported by pulleys 84 carried by a transverse shaft 85 rotatably mounted on brackets 86 secured on the bars 17 and pulleys 87 carried by a transverse shaft 88 rotatably mounted on brackets 89, on which the aforementioned shaft 12 is also rotatably mounted, secured to the outer ends of the bars 13 whereby the belts 83 may be removed without rendering the remaining portion of the top tape mechanism 82 inoperative for purposes hereinafter described.

A top tape mechanism, generally indicated at 91, is provided for the conveyor belts 49 and is driven by a crossed belt 92 engaged with the roller 42. See Fig. 5.

The piling table and sheet delivery shown are the same as usually supplied with the press, and the piling table is left in the same position with relation thereto as originally erected, the sheet delivery being converted to receive sheets from the belts 49 instead of from the opposite direction by reversing the carriage thereof upon the tracks 57, reversing the pusher finger mechanism comprising the pusher fingers 67, lever 68, shaft 69, and connecting rod 71, which are removably supported upon transversely spaced forwardly and rearwardly extending horizontal bars 93, secured at the side of the piling table frame below the tracks 57, by means of a carriage 94 carrying the shaft 69 and removably mounted on the bars 93 and a bracket 95 removably mounted on one of the bars 93 and carrying the lever 68, and substituting the arm 64 and stops 65 for the usual mechanism for operating the stop fingers 63.

The tape frame comprising the side bars 13 is vertically adjustable by reason of the inner ends of the bars being pivoted at 14 to the delivery frames 9 as before described, and it will be noted that this construction is the usual one supplied with the press for purposes of obtaining greater access to the inking mechanism of the press. This tape frame is movable from the position in which the bell crank levers 15 maintain it and is supported in a lower substantially hori-

zontal position, as shown by dot and dash lines in Fig. 2 at 96, by inwardly extending brackets 97 secured to transversely spaced rails 98 extending between and secured to the piling table 3 and delivery frames 9 as originally supplied with the press 1 and piling table. This tape frame is released from the bell crank levers 15 by removing headed screws 99 which secure arms of the bell crank levers to the tape frame, removing headed screws 101 which secure arms of the bell crank levers to the bars 17, swinging the bell crank levers on the studs 16 away from the tape frame to clear the same and resecuring the bell crank levers in their new position to the bars 17 to support the same by means of the screws 101 engaged in additional holes 102 of the bars 17, and replacing the screws 99 in the tape frame to support a transverse rod 103 thereof into the ends of which the screws 99 are screw-threaded. When this tape frame is so positioned, the sheet delivery when converted to receive sheets from the direction of the press, as originally arranged, receives sheets from the belts 7 in the same manner as it does from the belts 49 as shown. When the said tape frame is lowered the tapes 83 are removed leaving the remainder of the top tape mechanism free to lower with the tapes 7 and function therewith as before. In addition when the mechanism is converted to deliver directly from the press the brackets 84 with the rods 33 attached thereto are removed from the rod 35 and are attached in reverse position, as indicated in dot and dash lines in Fig. 2, on a transverse rod 104 above the tapes 7 and supported by brackets 105 secured to the bars 13, and when so positioned the rods 33 act as top guides for the sheets.

Thus the press and sheet delivery may be operated alone, the sheet delivery, tapes 6 and 7 and the top tape mechanism being driven by the press.

As before described the tapes 38, 45, 49 and top tape mechanism 91 are driven from the bronzing machine, and in order that the bronzing machine and sheet delivery may be operated alone means is provided for operating the sheet delivery from the bronzing machine as follows. A crank 106 is secured on the shaft of the sheet carrying cylinder 37 thereof, and a transverse rock shaft 107 is mounted in the frame of the bronzing machine at the rear end thereof.

See Fig. 5. An arm 108 is secured to the shaft 107 and is connected with the crank 106 by a connecting rod 109 whereby the shaft 107 is oscillated. A pair of lever arms 111 are secured at opposite ends of the shaft 107, and the outer ends of these arms may be connected with the trucks 58 of the sheet delivery carriage to reciprocate the same by connecting rods, similar to the connecting

rods 81 before described, indicated by dotted lines at 112 in Figs. 3 and 5. The portion of the sheet conveyor on the feed board 19 of the bronzing machine is removable as is usual so that the sheets may be fed to the cylinder 37 thereof by hand.

The press 1 is driven by a motor 113 through a belt 114, and the bronzing machine is driven from the press by a transmission chain mechanism 115 of usual construction which is enclosed between the press and bronzing machine by a casing 116 extending along the supporting floor.

While we have herein particularly described our invention we do not wish to be limited to the precise details described as changes may readily be made without departing from the spirit of our invention, but having thus described our invention, we claim as new and desire to secure by Letters Patent the following claims:—

1. The combination with two spaced sheet treating machines of a sheet receiving means disposed between said machines, means for conveying sheets from one of said machines and discharging them to said sheet receiving means at an elevated point, and sheet conveying means extending over said sheet receiving means and said sheet conveying and discharging means for conveying sheets from the other of said sheet treating machines to said last mentioned sheet treating machine.

2. The combination with two spaced sheet treating machines of a sheet receiving piling table disposed between said machines, means for conveying sheets from one of said machines and discharging them to said piling table, and sheet conveying means extending over said piling table and said first mentioned conveying means for conveying sheets from the other of said sheet treating machines to said last mentioned sheet treating machine.

3. The combination with a printing press and a bronzing machine disposed in spaced relation of a sheet receiving means disposed between the printing press and the bronzing machine, means for conveying sheets from the bronzing machine and discharging them to said sheet receiving means at an elevated point, and sheet conveying means extending over said sheet receiving means and said first mentioned sheet conveying means for conveying sheets from the printing press to the bronzing machine.

4. The combination with a printing press and a bronzing machine adapted for sheet feed and discharge from one end and having its sheet discharge point below its point of sheet feed and disposed in spaced relation with the printing press, with the said end thereof facing the sheet discharge end of the printing press, a sheet receiving piling table disposed between the printing press and the

bronzing machine, means for conveying sheets from the bronzing machine and discharging them to said piling table at an elevated point, and sheet conveying means extending over said piling table and said first mentioned sheet conveying means for conveying sheets from the printing press to the bronzing machine.

5. The combination with two spaced sheet treating machines of a sheet receiving piling table between said machines, means for conveying sheets from one of said machines and delivering them to said piling table including an elevated horizontally operating sheet delivery, and sheet conveying means extending over the piling table and said sheet conveying and delivering means for conveying sheets from the other of said sheet treating machines to the last mentioned sheet treating machine.

6. The combination with a sheet treating machine of a second sheet treating machine adapted for sheet feed and discharge from one end and having its sheet discharge point below its point of sheet feed and disposed in spaced relation with said first mentioned machine with the said end thereof facing the sheet discharge end of said first mentioned machine, sheet receiving means disposed between said machines, elevated means for conveying sheets from said second machine and delivering them to said sheet receiving means at an elevated point, and elevated sheet conveying means extending over said sheet receiving means and said first mentioned elevated means for conveying sheets from said first mentioned sheet treating machine to said second sheet treating machine.

40 7. The combination with a sheet treating machine of a second sheet treating machine adapted for sheet feed and discharge from one end and having its sheet discharge point below its point of sheet feed and disposed in spaced relation with said first mentioned machine with the said end thereof facing the sheet discharge end of said first mentioned machine, a sheet receiving piling table between said machines, means for conveying sheets from said second sheet treating machine and delivering them to said piling table including an elevated horizontally operating sheet delivery, and sheet conveying means extending over the piling table and said sheet conveying and delivering means for conveying sheets from the first mentioned sheet treating machine to said second sheet treating machine.

45 8. The combination with a sheet treating machine of a second sheet treating machine adapted for sheet feed and discharge from one end and having its sheet discharge point below its point of sheet feed and disposed in spaced relation with said first mentioned machine with the said end thereof facing

the sheet discharge end of said first mentioned machine, a sheet receiving piling table between said machines, elevated means for conveying sheets from said second sheet treating machine and delivering them to said piling table including a horizontally operating sheet delivery, and elevated sheet conveying means extending over the piling table and said first mentioned elevated means for conveying sheets from the first mentioned sheet treating machine to said second sheet treating machine.

9. The combination with a cylinder printing press of a cylinder bronzing machine adapted for rear delivery and having its sheet discharge point below its point of sheet feed and disposed in spaced relation with the press with its rear end facing the discharge end of the press, a sheet receiving piling table between said machines, means for conveying sheets from the bronzing machine and delivering them to said piling table including an elevated horizontally operating sheet delivery, and sheet conveying means extending over the piling table and said sheet conveying and delivering means for conveying sheets from the press to the bronzing machine.

10. The combination with a cylinder printing press adapted for front delivery of a cylinder bronzing machine adapted for rear delivery and having its sheet discharge point below its point of feed and disposed in spaced relation with the press with its rear end facing the front end of the press, a sheet receiving piling table between the press and bronzing machine, elevated means for conveying sheets from the bronzing machine and delivering them to said piling table including a horizontal belt conveyor and a horizontally operating sheet delivery cooperating therewith, and elevated belt conveyor means extending over the piling table and said first mentioned elevated means for conveying sheets from the press to the bronzing machine.

11. The combination with two sheet treating machines of a sheet receiving means, and means for conveying sheets from either sheet treating machine and delivering them to said sheet receiving means.

12. The combination with two sheet treating machines of a sheet receiving means, a sheet delivery for delivering sheets to said sheet receiving means, means for operating said delivery from either machine, a sheet conveyor operated by one of said sheet treating machines for conveying sheets from this machine to said sheet delivery, and a second conveyor operated by the other sheet treating machine for conveying sheets from this machine to said sheet delivery.

13. The combination with two spaced sheet treating machines disposed with their discharge ends facing each other of a sheet

receiving piling table disposed between said machines, a sheet delivery adapted for delivering sheets to said piling table and convertible to deliver sheets from the direction 5 of either sheet treating machine, means for operating said sheet delivery from either sheet treating machine, a belt conveyor operated by one of said sheet treating machines for conveying sheets from this machine to said sheet delivery when converted to deliver sheets from the direction of this machine, and a second belt conveyor operated by the other sheet treating machine for conveying sheets from this machine to said sheet delivery when converted to deliver sheets from the direction of this machine.

14. The combination with a sheet treating machine of a second sheet treating machine spaced therefrom, sheet receiving means disposed between said machines, a sheet delivery adapted for delivering sheets to said sheet receiving means and convertible to deliver sheets from the direction of either machine, a sheet conveyor for conveying sheets from said second machine to said sheet delivery when converted to deliver sheets from the direction of this machine, a second sheet conveyor extending over said sheet receiving means, said sheet delivery, and said first mentioned conveyor for conveying sheets from said first mentioned machine to said second machine and including a vertically adjustable conveyor unit operated by said first mentioned machine and adapted when in its lower position to convey sheets from said first mentioned machine to said sheet delivery when converted to deliver sheets from the direction of said first mentioned machine, and means for operating said sheet delivery from said first mentioned machine.

15. The combination with a sheet treating machine of a second sheet treating machine adapted for sheet feed and discharge from one end and having its sheet discharge point below its point of feed and disposed in spaced relation with said first mentioned machine with the said end thereof facing the discharge end of said first mentioned machine, a sheet receiving piling table disposed between said machines, an elevated horizontally operating sheet delivery adapted for

delivering sheets to said piling table and convertible to deliver sheets from the direction of either of said machines, a belt sheet 55 conveyor operated by said second machine for conveying sheets therefrom to said sheet delivery when converted for delivering sheets from the direction of this machine, a second belt conveyor extending over said piling 60 table, said sheet delivery, and said first mentioned conveyor for conveying sheets from said first mentioned machine to said second machine and including a vertically adjustable conveyor unit operated by said first 65 mentioned machine and adapted in its lower position to convey sheets from said first mentioned machine to said sheet delivery when converted to deliver sheets from the direction of said first mentioned machine, and means 70 for operating said sheet delivery from either of said machines.

16. The combination with a cylinder printing press of a cylinder bronzing machine adapted for rear delivery and having 75 its sheet discharge point below its point of feed and disposed in spaced relation with the press with its rear end facing the discharge end of the press, a sheet receiving piling table disposed between said machines, 80 an elevated horizontally operating sheet delivery adapted for delivering sheets to said piling table and convertible to deliver sheets from the direction of either machine, an elevated belt sheet conveyor operated by the 85 bronzing machine for conveying sheets therefrom to the sheet delivery when converted to deliver sheets from the direction of this machine, a second elevated belt conveyor extending over said piling table, said delivery, 90 and said first mentioned conveyor for conveying sheets from the press to the bronzing machine and including a vertically adjustable conveyor unit operated by the press and adapted in its lower position to convey sheets 95 from the press to the sheet delivery when converted to deliver sheets from the direction of the press, and means for operating said sheet delivery from the press.

In witness whereof we hereunto affix our 100 signatures this fifteenth day of August, 1922.

JACOB NIEMES.
HARRY B. ENGBERSEN.
